(57) **CLAIM**

The ornamental design for an external medication packaging, as shown and described.

DESCRIPTION

FIG. 1 is a top perspective view for an external medication packaging.

FIG. 2 is a back side view thereof;

FIG. 3 is a front side view thereof;

FIG. 4 is a right side view thereof;

FIG. 5 is a left side view thereof;

FIG. 6 is a bottom view thereof;

FIG. 7 is a top view thereof;

FIG. 8 is a top perspective view, shown in an open state; and, FIG. 9 is a top perspective view thereof, shown with exemplary blister packages.

The broken lines in the drawings represent unclaimed subject matter and form no part of the claim.

The evenly broken lines are shown for the purpose of illustrating environmental subject matter of exemplary blister packages and form no part of the claimed design.

The heavy oval dashed lines shown on the top surface of FIGS. 1, 7, 8 and 9 represent perforations that form part of the claimed design.

1 Claim, 9 Drawing Sheets
